FLORAL BASKET AND ANCHORING MEANS FOR FUNERAL USE

George L. Wilkins, Cape Charles, Va.

Application June 8, 1954, Serial No. 435,220

2 Claims. (Cl. 47—41)

This invention comprises novel and useful improvements in a floral basket and anchoring means for funeral use and more specifically pertains to an improved construction of floral basket which will permit the latter to be placed in normal manner upon flat, horizontal surfaces or will selectively enable the same to be anchored in an unobtrusive but secure manner upon inclined surfaces.

Floral baskets for funeral purposes, in order to be acceptable for such use, must satisfactorily conform to and meet certain requirements which are peculiar to this field of use. Thus, on the occasions when such baskets are utilized, it is an indispensable requisite that they shall possess a grace and dignity of appearance which is not marred by an obtrusive appearance of attachments or gadgets. In addition, it is extremely important that a single basket shall be provided wherein the funeral flowers may remain in the same basket without change when displayed on flat, level or horizontal surfaces as by the casket in the home or in the undertaking parlor; and yet, which may be placed about the grave during the funeral ceremony, without any danger of tipping even though placed upon slopes or the inclined sides of mounds.

It is therefore the primary object and purpose of this invention to provide a floral basket peculiarly adapted to meet the rigid requirements of funeral use as outlined above.

A further and more specific object of the invention is to provide a floral basket having a novel, improved and unobtrusive arrangement of anchoring means whereby the basket may function in a normal manner for holding and displaying flowers upon flat and horizontal surfaces, as upon tables and the like, and yet may also, by means of retractile anchors, be securely positioned upon inclined surfaces as at the grave.

A further and more specific object of the invention is to provide a floral basket for funeral use having retractile anchoring pins which shall be associated therewith in a novel manner whereby the pins in retracted position will in no way interfere with the normal use of a basket upon a flat horizontal surface; and whereby the pins will be yieldably retained in a retracted and unobtrusive manner ready for use; and whereby the pins may be advanced below the base of the basket for anchoring the same in an unobtrusive manner.

Yet another specific object of this invention is to provide a floral basket construction as set forth in the preceding objects wherein the anchoring pins shall be provided with headed points which will enhance and facilitate the anchoring engagement of the pins; and yet, which will prevent embarrassing and unintentional withdrawal of the pins from the basket when the pins are moved into their retracted position.

Still another important object of the invention is to provide a floral basket in conformity with the above mentioned objects wherein provision is made for receiving the pointed ends of the anchoring pins within the base structure of the basket.

A final important object of the invention to be spe-

2

cifically enumerated herein is to provide in a floral basket in conformity with the previously mentioned objects, the provision of unobtrusive means whereby the anchoring pins may be releasably secured against the sides or handle of the basket in a readily releaseable manner, in the retracted position of the anchoring pins.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of one form of floral basket disclosing the manner in which the anchoring means in accordance with this invention is applied thereto, the anchoring pins being shown in retracted position;

Figure 2 is a side elevational view of Figure 1, but indicating the manner in which the anchoring pins are positioned for securing the basket against tipping;

Figure 3 is an enlarged detail view taken in vertical section through the base of the basket of Figures 1 and 2 and showing the manner in which the anchoring pins are retracted into the base in the retracted position of the pins;

Figure 4 is a detail view taken upon an enlarged scale substantially upon the plane indicated by the section line 4—4 of Figure 1 and showing one form of resilient retaining means for holding the anchoring pins in retracted position;

Figure 5 is a detail view taken substantially upon the plane indicated by the section line 5—5 of Figure 1, and upon an enlarged scale, and showing a retaining and guide construction for the lower end of the anchoring pins;

Figure 6 is a perspective view of a portion of the pointed extremity of one of the anchoring pins;

Figure 7 is a view similar to Figure 1, but showing the manner in which the anchoring means of this invention is applied to a second form of floral basket commonly employed for funeral purposes;

Figure 8 is a detail view taken upon an enlarged scale substantially upon the plane indicated by the section line 8—8 of Figure 7 and showing the manner in which the anchoring pins are releasably retained in retracted position in an unobtrusive manner and against the handle of the basket;

Figure 9 is an enlarged detail view taken in vertical section through a portion of the base of the basket and showing in full lines the position of the anchoring pin in retracted position and in dotted lines the position assumed by the pin when the same is in operative position;

Figure 10 is a detail view taken upon an enlarged scale substantially upon the plane indicated by the section line 10—10 of Figure 8 and showing the manner in which the retaining means for yieldingly holding the anchoring pin in retracted position is unobtrusively associated with the handle of the basket; and

Figure 11 is a detail view taken upon an enlarged scale substantially upon the plane indicated by the section line 11—11 of Figure 8 and showing the manner in which a guiding means for the anchoring pin is unobtrusively mounted upon and secured to the handle of the basket.

Floral baskets for funeral purposes are generally of two types, these two types being shown in Figures 1 and 7. Reference is made first to Figures 1—6 for an understanding of the manner in which the principles of the invention are applied to the form of floral basket disclosed in Figure 1.

The basket of Figure 1 includes a frusto-conical body 10 of any desired construction having a carrying handle 12 attached to the upper end thereof, and being mounted at its lower end upon an inverted dish-shaped base 14.

In one conventional form, this base has a top wall 16 which constitutes a bottom for the basket body 10, being attached thereto as by soldering, as indicated at 18, the base having a downwardly and outwardly flaring rim or side 20 together with a supporting flange 22 constituting an annulus at the bottom of the rim. Baskets of this nature are entirely satisfactory for containing flowers at a funeral and for being supported upon a flat and substantially horizontal surface, as upon a casket, a casket tressel, the floor or table or the like of a home or funeral parlor. However, when it is desired to carry the floral basket to a grave and dispose the same about the grave, difficulty is frequently encountered since any inclination or slope of the ground at the grave or surface upon which the basket is to rest, or wind or the like will readily cause the basket to upset, producing an extremely annoying and undesirable effect upon the solemnity of the occasion.

In order to overcome this difficulty and yet in no way mar the graceful and attractive appearance of the floral basket or intrude upon the dignity and solemnity of the occasion, there is provided an improved anchoring means. In this embodiment, the anchoring means comprises two or more anchoring pins 24 of any desired material and which at their lower ends are provided with points 26 together with triangular-shaped wings, lugs, ribs or projections 28. The shape of the point and the wings facilitates penetration of the end of the rods into the ground upon which the base 14 is supported and, as will be apparent from Figure 2, effectively prevents the possibility of accidental overturning of the basket. The rods are slidably received in suitable apertures 30 in the top wall 16 of the base, these apertures being as closely adjacent to the lower end of the side wall of the body 10 of the basket as possible in order to minimize any obtrusive appearance of the anchoring rods. The headed pointed ends of the rods are of such size that the same may be snugly received within the chamber of the inverted dish-shaped base, as shown in Figure 3, so that in the raised or retracted position of the anchoring rods, there will be no possibility of their points marring a table top or other supporting surface upon which the floral basket may be disposed.

In order to maintain the rods closely against the side of the body 10 in an unobtrusive manner, there are provided one or more retainers and guides 32, see also Figure 5, which are positioned closely adjacent the base 14 and in which the rods are slidably received. These guides assist in preventing rattle of the rods against the side of the basket; serve to guide and retain the rods closely adjacent the side of the basket in an unobtrusive position; and facilitate vertical sliding movement of the rods to their extended operative position or to their retracted inoperative position, as shown in Figures 2 and 3, respectively.

In order to retain the rods in a retracted position, as shown particularly in Figure 4, there is provided a retaining finger 34 of any suitable material, preferably of a resilient nature. This finger, which may consist of a thin sheet metal resilient strip, may be secured at one end as by a rivet or the like 36 and at its other extremity may have an outwardly curving lip 38 to facilitate movement of the rod into and out of the arcuately shaped central portion 40 of the clip.

At its upper end, each of the anchoring pins may be provided with an outturned portion 42 constituting a finger grip member whereby the rod may be manipulated.

From the foregoing, it will be readily apparent that in the raised position of the anchoring pins, they may be inserted between the resilient clip 34 and the wall of the body 10, where they will be resiliently and securely held against rattling or against accidental displacement and in a very unobtrusive manner. In the raised position, the members 28 will engage the undersurface of the top wall 16 of the base and prevent further upward movement of the rods and thereby prevent accidental removal of the

rods from the basket. When it is desired to extend the rods into operative position, the portion 42 may be grasped, the rods may be shifted slightly sidewise to disengage the same from the resilient clip 34 through the open lip 38 of the same, and the rods then pushed downwardly into their extended position, thereby securely anchoring the basket upon inclined surfaces.

Reference is next made to Figures 7-11 showing the manner in which the principles of this invention are applied to the other conventional form of floral basket shown in Figure 7. In this form, the floral basket includes a body 50 of any conventional design having usually a flat plate-like base 52 which may be either solid or of an inverted dish-shape, the solid form being illustrated in Figures 7-9. The basket further includes a handle having a bail 54 with a pair of inclined arms 56 by which the handle is attached to the base in a slightly spaced relation to the lower end of the frusto-conical body 50, as will be apparent from Figures 7 and 9. In this form, as shown in Figure 9, the body 50 has its own bottom wall 58, secured to the base in any desired manner, not shown. In this type of basket, a pair of anchoring pins 60 are disposed in closely adjacent relation to the handle arms 56. As shown, they are disposed upon the outside of these arms but closely adjacent thereto, although sufficient space exists between the arms and the basket that they may be disposed upon the interior of the arms. In any event, they are retained as close to the arms as possible in order to render them as unobtrusive as possible. The anchoring pins are provided with pointed extremities 62 together with a slightly enlarged shoulder 64 thereabove. The base, if of solid construction, is provided with a countersunk bore 66 for receiving the head of the rod and permits the same to be retracted into the bore to thus prevent the possibility of the points marring a table top or other supporting surface when the basket is used in the normal manner for placing flowers upon flat surfaces. However, as in the preceding embodiment, the enlarged portion of the end of the rods prevents accidental vertical upward withdrawal of the rods from the base.

In order to retain the rods in a retracted position, there is provided a resilient clip generally indicated by the numeral 68 for each rod, this clip being shown particularly in Figure 10. This clip may be of wire, thin sheet metal or any other suitable material and which is preferably of resilient nature. The clip includes a shank portion 70 which at one end is provided with a resilient hook 72 having a curved lip 74 for resiliently retaining the anchoring pin 60. At the other end, the shank 70 is looped or folded upon itself, as at 76, after being passed through the braided material of the handle 56, as clearly shown in Figure 10. By this means, the clip is unobtrusively but securely attached to the handle arms and when so attached, is effective to resiliently but releasably receive and retain the anchoring pins 60 which, as in the preceding embodiment, may have a laterally turned finger grip portion 78.

There may also be provided guide members for the lower portions of the rods, of a construction particularly shown in Figure 11. These guide members, designated generally by the numeral 80, preferably comprise a shank portion 82 having a looped extremity 84 extending through and about the woven material of the handle arm 56, and also having an eyelet 86 which slidably receives the lower portion of the pin 60.

The operation and novel advantages of this form of the invention are identical with those previously described in connection with the embodiment of Figures 1-6.

It will be observed that in this form, as in the preceding form, the anchoring pin is positioned in the most unobtrusive manner possible upon the basket; is resiliently held in retracted position; is provided for means facilitating its penetration of the soil to secure a good

anchoring engagement, and also prevent accidental withdrawal of the pin from the basket, and is guided in its vertical travel.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. A floral basket comprising a body adapted to hold flowers, an enlarged base on a lower portion of said body having a flat lower surface for supporting said body and a handle secured to said body; retractile anchor means carried in converging angular relation on opposite side portions of said body and in close disposition thereto, the base including a downwardly opening lower recess portion in communication with aperture portions extending through said base, said retractile anchor means including elongated anchor pins reciprocably received within said aperture portions, said pins including a lower enlarged pointed end receivably retained within the lower recess portion of said base, said pointed end being extensible downwardly from said base for penetration into the ground and being retractable upwardly, a guide ele-

5

10

15

20

25

ment carried on said basket for each anchor pin, said guide element including a portion extending around the circumference of said anchor pins and reciprocably receiving said anchor pins for guiding the reciprocable movement of said anchor pins relative to said basket, and a resilient securing element carried on said basket in vertically spaced relation to each said guide element for receiving an upper portion of said anchor pin for retaining the same in retracted position with the enlarged lower pointed end thereof located wholly within said recess, said resilient securing element including an arcuate portion terminating in an outwardly curving lip for facilitating the removable retention of said anchor pin.

2. A floral basket as set forth in claim 1 wherein said guide element and resilient securing element are carried closely adjacent to said handle and to said base respectively.
